SET STABILIZER FOR PAPER WINDERS

Rubel M. Johnson, Crossett, Ark.

Application April 17, 1941, Serial No. 389,066

7 Claims. (Cl. 287—52.03)

This invention relates to a means to prevent the set of rolls from slipping while being wound in a paper winding machine.

It is particularly aimed to provide a construction using a novel collar adjustable on a sleeve mounted by a winder shaft, for engagement by the paper at one edge while being wound.

It is further aimed to provide a construction wherein the collar is capable of movement in one direction only namely toward the paper edge and which has a ratchet connection along the mounting sleeve and means whereby the connection may be released when desired.

The more specific objects and advantages will become apparent from a consideration of the description following taken in connection with the accompanying drawings illustrating an operative embodiment.

In said drawings:

Figure 1 is a view partly in elevation and partly in section, showing the use of my invention in connection with the winder shaft in a paper winding machine;

Figure 2 is an enlarged view primarily in central longitudinal section showing the collar, its mounting and association with the winder shaft and paper roll;

Figure 3 is an edge elevation of the collar;

Figure 4 is a detail section taken on the line 4—4 of Figure 3;

Figure 5 is a view primarily in side elevation, but partly broken away and in section, of the ring or collar;

Figure 6 is a diametric section taken on the line 6—6 of Figure 5;

Figure 7 is a view similar to Figure 5 of a modified form;

Figure 8 is a diametric section taken on the line 8—8 of Figure 7;

Figure 9 is a view similar to Figure 5 but through a second modified form;

Figure 10 is an edge elevation of the form of ring or collar of Figure 9;

Figure 11 is a section taken on the plane of line 11—11 of Figure 10;

Figure 12 is a section taken on the plane of line 12—12 of Figure 9, and

Figure 13 is a detail section taken on the line 13—13 of Figure 9.

Referring specifically to the drawings wherein like reference characters designate like or similar parts, 10 designates a conventional winder shaft of a paper winding machine in connection with which a removable core 11 constituting usual equipment, is used, and upon which a roll of

paper or the equivalent 12 is wound through the operation of the machine.

In carrying out my invention, a sleeve 13 is removably disposed upon the shaft 10 with one end in abutment with the core and adjacent which end, sleeve 13 is peripherally grooved as at 14, to provide ratchet rings or teeth 15. Such sleeve 13 is suitably positioned through the aid of sleeves 16 of any desired number, placed end to end in contact with each other and with the sleeve 13 and held in place by a nut 17 engaged with screw threads 18 of the winder shaft 10.

Applicable over the sleeves 13 and 16 is a removable ring or collar 19, whose bore is smooth so that it may slide over the ratchet teeth or rings at 15. Such collar 19 has radial openings at 20 in which dogs 21 are slidably disposed to engage the grooves 14 and hold the collar in abutment with the paper 12 at one edge. Such dogs are chamfered at 22 at their inner edges longitudinally so as to fit the grooves 14 and they are concave circumferentially as shown at 23, to better conform to the periphery of sleeve 13 at the grooves 14. Such dogs 21 may be of any desired shape in cross section. Due to the particular shaping of the teeth and the grooves 14 and ratchet teeth 15, it will be clear that the collar 19 is capable of movement only from left to right in Figures 1 and 2 and thus cannot be moved from right to left in such figures. Also, the inner ends of some of the dogs may be cut away as at 24, so that the dogs will engage the ratchet teeth some before others, and thus giving a more graduated adjustment on the sleeve 13. As particularly shown in the first form of the invention, the dogs may be rectangular in cross section.

Disposed peripherally of the ring or collar 19, are spring blades 25 of arcuate formation, fastened to the collar as by means of screws 26 and having their free ends outwardly deflected as at 27. Dogs 21 are suspended in the recesses 20 by the springs 25 by means of screw elements 28 engaging the dogs, passing through the springs and having heads at 29, whereby they may be engaged to manually retract the dogs if desired. Any ratcheting action of the dogs over the teeth 15, will be against the tension of the springs 25 as will be understood.

The periphery of the collar is recessed as at 30 and has an annular groove at 31, in communication with the recesses. The springs 25 are accommodated in the recesses and a ring 32, preferably externally knurled, as shown, is rotatably mounted in the groove 31 and at the points of connection between groove 31 and recesses 30,

cam members 31', are disposed. Such cam members consist of triangular portions 32' and lugs 33 riveted at 34 to the ring 32. As a result of the construction described, the ring 32 may be partially rotated whereby the cams 31' move under the deflected ends 27, thereby lifting springs 25 at such ends and lifting or retracting the dogs 21 so that they disengage the grooves 14 and ratchet teeth 15.

It will be understood that the sleeve 13 and coacting collar 19 and associated parts may be used at both ends of the paper roll 12, if desired, and that if desired, one of the collars need not be provided with the ring 32 and the cam members 31' as it is necessary to remove but one of the collars 19, in removing the roll 12 from the machine.

Various changes may be resorted to provided they fall within the spirit and scope of the invention. For instance I may use the modified form of Figures 7 and 8. In such form, the dogs 21a function like those at 21 but are preferably cylindrical in form. They are mounted by springs 25a but in lieu of the fastening 28-29, the springs 25 pass removably through undercut slots 35 provided in the upper ends of the dogs 21a. In all other respects, the modified form of Figures 7 and 8 corresponds to that of the first form of the invention. It is clear that any desired number of the dogs may be used in any form of the invention.

Another form or modification is shown in Figures 9 to 13. Here, the ring 32b functions like that at 32 but is preferably made up of arcuate sections 36, overlapping at their ends at 37 and being riveted together at 38. Lugs 33b are riveted at 34b to the sections 36 and carry cams 31b corresponding to those at 31'. The dogs in this form are also cylindrical and are designated 21b and are suspended by springs in the form of wires at 25b corresponding to and functioning like those at 25 and 25a, and being fastened in place by screws at 26b. Such wires 25b pass through openings 27 in the upper ends of the dogs 21b removably. Expansive springs 39 occupy recesses 40 in the collar 19b which are under compression and engage the sections 36, frictionally holding the latter against accidental turning or rotation.

I claim as my invention:

1. In a set stabilizer for a winder shaft, a sleeve applicable to a shaft and having ratchet means thereon, a collar movable over the ratchet means to engage a roll, said collar having dogs radially movable to engage and disengage the ratchet means, means urging movement of said dogs toward the ratchet means consisting of a plurality of blade springs disposed peripherally of the collar fastened adjacent one end to the latter and adjacent the other end suspending and having the dogs fastened thereto.

2. In a set stabilizer for a winder shaft, a sleeve applicable to a shaft and having ratchet means thereon whose effective abutment surfaces are crosswise of the shaft, a collar movable over the ratchet means to engage a roll, said collar having dogs radially movable to engage and disengage the ratchet means, blade spring means urg-

ing movement of said dogs toward the ratchet means, and means operable on the collar to retract the dogs.

3. In a set stabilizer for a winder shaft, a sleeve applicable to a shaft and having ratchet means thereon, a collar movable over the ratchet means to engage a roll, said collar having dogs radially movable to engage and disengage the ratchet means, means urging movement of said dogs toward the ratchet means consisting of a plurality of blade springs disposed peripherally of the collar and suspending the dogs, recesses in the periphery of the collar in which said blade springs are disposed, a groove in the periphery of the collar, and means operable in the groove having parts extending laterally therefrom into the recesses engageable with the springs to retract them and the dogs therewith.

4. In a set stabilizer for a winder shaft, a sleeve applicable to a shaft and having ratchet means thereon, a collar movable over the ratchet means to engage a roll, said collar having dogs radially movable to engage and disengage the ratchet means, means urging movement of said dogs toward the ratchet means, consisting of a plurality of springs disposed peripherally of the collar and suspending the dogs, recesses in the periphery of the collar having parts engageable with the springs to retract them and the dogs therewith, said parts consisting of cams, and said springs having outwardly deflected portions directly engageable by the cams.

5. In a set stabilizer for a winder shaft, a sleeve applicable to a shaft and having ratchet means thereon, a collar movable over the ratchet means to engage a roll, said collar having dogs radially movable to engage and disengage the ratchet means, consisting of a plurality of springs disposed peripherally of the collar and suspending the dogs, said dogs having recesses through which the springs pass to mount the dogs.

6. In a set stabilizer for a winder shaft, a sleeve applicable to a shaft and having ratchet means thereon, a collar movable over the ratchet means to engage a roll, said collar having dogs radially movable to engage and disengage the ratchet means, consisting of a plurality of springs disposed peripherally of the collar and suspending the dogs, said dogs having recesses through which the springs pass to mount the dogs, said springs being metallic wires.

7. In a set stabilizer for a winder shaft, a sleeve applicable to a shaft and having ratchet means thereon, a collar movable over the ratchet means to engage a roll, said collar having dogs radially movable to engage and disengage the ratchet means, means urging movement of said dogs toward the ratchet means, consisting of a plurality of springs disposed peripherally of the collar and suspending the dogs, a ring rotatable on the collar, means on the ring engageable with said springs to retract them and the dogs therewith, said collar having a recess, and a spring in said recess engaging the ring to prevent accidental rotation of the latter relatively to the collar.

RUBEL M. JOHNSON.
